EDGE BINDER FOR FURNITURE WITH COVERED METAL TOPS

Karl E. Castle, Washington, D. C., assignor to
Invincible Metal Furniture Company, Mani-
towoc, Wis., a corporation of Wisconsin

Application June 2, 1949, Serial No. 96,685

4 Claims. (Cl. 311—107)

1

This invention relates to improvements in furniture with a covered metal top.

The invention has for its objectives the provision of a metal top which, when covered with linoleum or the like, will have a pleasing appearance and provide substantially a full, flat, working surface while nevertheless retaining a modernistic rounded edge appearance.

It is a further object of the invention to carry the facing material, which may comprise linoleum or other sheet material, over the edges of the metal top to provide a thermally non-conductive support for the arms of the person using the desk, a binding strip for the covering material being provided at a lower level but in a position to offer better than average protection against scratching or other damage to the linoleum or other facing material.

It is a still further object of the invention to provide an arrangement in which the binding strip not only affords an attractive finish bead, but also constitutes means for positively anchoring the facing material, thereby supplementing the cement commonly used for attaching a facing material to a metal top.

It is a further object of the invention to provide an arrangement in which the downward bias of the top toward the furniture, however effected, is transmitted through supporting arms to a binding strip which is shouldered for engagement with a rim on the furniture and is beaded and provided with an inwardly directed margin urged toward the top by the pivoting of the binding strip on the rim under the bias of said top.

The present application is a companion to an application Serial No. 96,712, filed by Leroy W. Pasewalk and John F. Reimer on June 2, 1949, and entitled Capped Corner and Metal Top Anchorage for Furniture.

In the drawings:

Fig. 1 is a fragmentary view in perspective showing in relatively separated positions certain of the component parts of a furniture top construction embodying this invention.

Fig. 2 is a fragmentary detail view taken in transverse section on the line 2—2 of Fig. 4.

Fig. 3 is a fragmentary detail view in transverse section showing the parts disassembled.

Fig. 4 is a fragmentary detail view in perspective showing the parts illustrated in Fig. 2.

While the invention is shown exemplified in a metal desk construction, it will be understood that it is suitable for other furniture, and even for non-metallic furniture if desired. The desk

generically designated by reference character 5 may be of any suitable metallic or wooden structure. Securely fixed thereto, as by means of the bolts 6, is a rim 7 of angular form in cross section, the rim having a horizontal inwardly directed flange at 8 and a continuous upstanding flange at 9.

The metal top 10 has a substantially flat top surface bounded by marginal cylindrically curved portions at 11 which merge with vertical wall portions 12 at the sides and ends of the top. The lower margins of such wall portions are flanged inwardly at 13 (Figs. 2 and 3).

The top 10 is covered with a surfacing ply 15 which conventionally is made of linoleum or the like, although any other non-metallic sheet material such as plastic or leather or fabric may be used. The surfacing ply 15 is desirably cemented as usual to the top 10, to cover the upper surface of the top, the cylindrically rounded margins 11 and at least portions of the sides 12. The corners may be finished as disclosed in the companion application above identified, being covered by the cover caps 16, which are desirably made of stainless steel or the like.

To assure the anchorage, as well as the protection of the downwardly flanged edges 17 of the surfacing ply 15, binding clips are employed to anchor a binding strip which is decorative as well as protective. The binding strip 18 extends continuously about the top, being endless as applied. Its overall dimensions are such that it fits snugly within the upstanding flange 9 of the rim 7. At 19, it is outwardly flanged to form a shoulder which rests on the top margin of the flange 9 of the rim. Thence the binding strip is reversely curved at 20 to provide a bead, the inner margin 21 of which rests against the surfacing ply as shown in Fig. 2 and Fig. 4.

Fixed interiorly to the binding strip, as by the spot welds at 22, is the angular clip 23, the horizontal leg portion 24 of which is of just sufficient length to underlie the flange 13 of the top 10. The upturned finger 25 at the inner end of the clip is engaged by the inner margin of flange 13.

In consequence of this arrangement, the binding strip may be applied to the covered top as shown in Fig. 3 in advance of the assembly of the top to the rim 7 of the furniture. When the assembly of top and binding strip is inserted into the flange 9 of the rim, it will fit snugly therein, as shown in Fig. 2.

So far as the present invention is concerned, any desired means may be used for maintaining

the top, the rim and the binding strip in assembly. It is, however, preferred to use the means disclosed more particularly in the companion application above identified and illustrated in the accompanying drawings.

It will be observed in Fig. 2 that the horizontal leg 24 of the binding clip 23 does not fully seat against the flange 8 of the rim 7 when the shoulder 19 of the binding strip engages the upper margin of the flange 9 of the rim 7. The 10 inwardly directed flange 13 carried by the side and end walls of the top is thus left without any direct support and its inherent resilience is used for anchorage purposes.

To this end the horizontal flange 8 of rim 7 is provided at intervals with mounting plates 21 which are connected thereto by any desired means such as the spot welding shown in Fig. 4. These plates 21 are desirably embossed upwardly at 28 to provide bearings, as well as clearance for the heads of the rivets 29 used to fulcrum the respective clamps 30. These clamps desirably have embossed bearing portions 31 complementary to the embossed bearing portions 28 of the plates upon which they are mounted. Each clamp pivots on its rivet 29 subject to manipulation by means of a handle at 32. The ends of each of the clamping members 30 are provided with upwardly turned camming wings 33 which, in the position of the clamps shown in Fig. 1, are out of contact with the top flanges 13 but, on rotation of the respective clamps to the position shown in Fig. 4, ride on to the flanges 13 to exert downward clamping pressure on such flanges and thereby securely anchor the top to the rim and to the furniture carrying such rim. In the case of a desk, the clamps are readily accessible through the drawer openings and they are provided at intervals around the entire inner perimeter of the rim, as clearly shown in Fig. 1.

The arrangement disclosed is such as to provide an exceptionally rigid connection of the top to the piece of furniture while, at the same time, making the replacement of the top surfacing ply 15 extremely easy. It is only necessary to turn all of the clamps to the center position in which they are illustrated in Fig. 1 to completely release the top, which may thereupon be lifted not only from the rim but from the binding strip, its surfacing ply being thereby completely exposed for repair or replacement.

Yet, when the top is anchored by the several clamps as herein disclosed, the clamps not only hold the top to the desk but, by reason of the fact that the top flanges 13 are supported on the inwardly projecting arms 24 of the intervening clips 23, the binding strip is also anchored and released by the same manipulation of the clamps 30. The binding strip, in turn, has its margin 21 drawn snugly against the cover ply 15 so that regardless of what may happen in the course of years, to the adhesive originally used in the application of the cover ply 15, the ply will nevertheless remain securely bound to the top until the clamping pressure of the pivoted clamps 30 is released.

The height of the handle 32 is preferably such that as the camming action of the clamp 30 is exerted to draw the top 10 downwardly, the inner surface of the top will engage the upper end of the handle so that the pressure thereon will tend to bind the clamp and hold it in position.

In addition, the camming wings at the ends of the respective clamps will, in the final positions of adjustment thereof, engage the inner faces of

the depending wall portions of the top, further binding the parts against displacement or vibration.

The downward bias of the clamps upon the top not only securely holds the binding strip but further tends to cause the bead portions thereof to fulcrum on the upper margin of the rim, thereby pressing the free terminal margins of the bead more securely against the cover ply with which the top is surfaced.

What is claimed is:

1. The combination with a piece of furniture provided with a substantially continuous upstanding marginal rim, of a top having a depending upright wall disposed within the rim and provided with inwardly turned flange means, a substantially continuous binding strip intervening between said rim and said wall, and having a shoulder seated on the top of said rim, said strip being provided with top supports extending inwardly beneath said flange means in supporting relation thereto and free of permanent connection therewith, and clamp means connected with the furniture and engaged with the flange means of said top and acting thereon to hold said top to said furniture while exerting downward pressure through said supports upon said binding strip, said binding strip comprises a bead portion extending curvilinearly from said shoulder inwardly toward said wall and having a free margin embracing said wall below the level of said top, said top including a facing lamination engaged by said margin.

2. The combination with a piece of furniture having a substantially continuous upstanding marginal rim provided with an inwardly directed substantially horizontal flange, of a metal top having rounded marginal portions and depending wall portions provided with inwardly directed terminal flange means spaced from the rim flange aforesaid, a cover ply on said top extending at least partially downwardly over the external surfaces of said wall, and a binding strip extending substantially continuously within said rim between the rim and the cover ply and having a head capping the margin of said rim and terminating in an inwardly directed portion engaging the cover ply, the said binding strip having inwardly directed supporting means along its bottom portion extending beneath the flange means of the top at a level to support the top from the engagement of said bead with said rim, together with anchorage means interiorly engaging the flange of said top and connected with said furniture for holding said top to the furniture and said binding strip bead to said rim.

3. An edge binder for furniture having a top covered with a laminated facing, said furniture having a seating rim with an upturned marginal flange and the top comprising an inverted pan having depending wall portion disposed within said flange, said binder comprising a strip having an intermediate portion confined between the said flange and wall, a trim portion marginally superimposed on the top edge of the said flange and engaged with the laminated facing of said top, and an anchor portion extending inwardly beneath said wall to overlie said seating rim, the laminated facing of the top having a lower margin confined between the intermediate portion of said binding strip and said wall, said trim portion of the strip comprising a bead above said lower margin.

4. An edge binder for furniture having a top covered with a laminated facing, said furniture

having a seating rim with an upturned marginal flange and the top comprising an inverted pan having depending wall portion disposed within said flange, said binder comprising a strip having an intermediate portion confined between the 5 said flange and wall, a trim portion marginally superimposed on the top edge of the said flange and engaged with the laminated facing of said top, and an anchor portion extending inwardly beneath said wall to overlie said seating rim, the 10 wall of said top being provided with an inturned marginal flange overlying said seating rim to confine the anchor portion of the binding strip therebetween.
